(57) **CLAIM**

The ornamental design for the vehicle window with color decal as shown and described.

DESCRIPTION

The patent or application file contains at least one drawing executed in color. Copies of this patent or patent application publication with color drawing(s) will be provided by the Office upon request and payment of the necessary fee.

FIG. 1 is an inside view of the vehicle window with color decal according to the present design;

FIG. 2 is an outside front perspective view with open doors of the vehicle window with color decal on a vehicle according to the present design; and,

FIG. 3 is an outside back perspective view with open doors of the vehicle window with color decal on a vehicle according to the present design.

The broken lines illustrate portions of the vehicle window with color decal that form no part of the claimed design.
